UNITED STATES PATENT OFFICE

127,972

DESIGN FOR A PHONOGRAPH RECORD HOLDER

Luther I. Replogle, Oak Park, Ill., assignor to Replogle Globes, Inc., Chicago, Ill., a corporation of Illinois

Application May 9, 1941, Serial No. 100,874

Term of patent 7 years

To all whom it may concern:

Be it known that I, Luther I. Replogle, a citizen of the United States, residing at Oak Park, in the county of Cook and State of Illinois, have invented a new, original, and ornamental Design for a Phonograph Record Holder, of which the following is a specification, reference being had to the accompanying drawing, forming part thereof.

The figure is a perspective view of a phonograph record holder embodying my new design.

I claim:

The ornamental design for a phonograph record holder, as shown.

LUTHER I. REPLOGLE.
